UNITED STATES PATENT OFFICE.

WILLIAM M. VENABLE, OF PITTSBURGH, PENNSYLVANIA, ASSIGNOR TO BLAW-KNOX COMPANY, A CORPORATION OF NEW JERSEY.

TURNTABLE.

Application filed July 11, 1922. Serial No. 574,129.

To all whom it may concern:

Be it known that I, WILLIAM MAYO VENABLE, a citizen of the United States, residing at Pittsburgh, in the county of Allegheny and State of Pennsylvania, have invented certain new and useful Improvements in Turntables, of which the following is a specification.

My invention relates to turntables suitable for turning road vehicles, and especially useful for turning automobile trucks as an incident of road construction. The invention is particularly advantageous for turning heavily loaded trucks in a relatively narrow space, or on steep grades.

Hitherto, turning of trucks under such circumstances has been accomplished only with difficulty or inconvenience, at best; but with my turntable, it can be done quite readily.

In the construction of concrete roads, for instance, it is usual to prepare the subgrade with so-called "side rails" or forms at either side, and afterward fill in between such side rails with concrete to form the road. For this latter purpose, the concrete is distributed from a mixer, which is shifted ahead along the subgrade as the work advances. The broken stone, sand or other ingredients are delivered to the mixer by motor trucks, which must generally approach it over the subgrade, dump their loads, and then return in the direction whence they came. The trucks must, therefore, be turned around.

As a general rule, such roads are about 18 feet in width, more or less, and it is found desirable to employ five ton trucks for hauling the road materials. It is practically impossible, however, for a five ton truck to turn itself in anything like the space between the side rails of such a roadway; and even if the side rails were removed or omitted in an appropriate section of the prepared roadway, sufficient room would not always be available,—to say nothing of the difficulty and damage incident to having the trucks work back and forth at the steep sides of the subgrade. In road building on any considerable scale, therefore, it is often desirable to provide a turntable for turning the trucks. This turntable should preferably be so lo-

cated that a loaded truck can drive on and be turned around; then back off to the mixer and dump its load; and finally return (front 55 first) in the direction whence it came. In order that the returning truck may not have to drive over the turntable, it is desirable to place the latter in one side of the roadway, leaving room at the other side for the truck 60 to pass.

Many trucks, however, are of such wheel-base length (diagonally, from one front wheel to the rear wheel on the other side) that even with a turntable they cannot be 65 turned between side rails 18 feet apart,—not even, in fact, if the handicap involved in placing the turntable to one side of the road as above described did not exist. Even when the diagonal wheel-base lengths is as low 70 as 14 feet, moreover, it is impossible to "balance" such a loaded truck (to permit of its being turned quite easily) on any turntable that can be operated in an 18 foot roadway. For as trucks are ordinarily constructed, 75 some 70% of the weight is carried on the rear wheels (which drive), and only 30% on the front wheels; so that in order to balance a truck of 14 foot wheel-base, the rear wheels should be about 4 feet back of the 80 turning center, and the front wheels about 10 feet forward from the center. To allow the truck to drive on the table from either end and be properly balanced, then, the turntable would have to be over 20 feet long,— 85 which is out of the question.

In actual practice, turntables hitherto used for road work have been made only 14 or 15 feet in diameter, in order that they may be set and swing within the roadway; and it has been impossible to center trucks over the turning center. When such a turntable can be set level, the additional friction entailed by eccentric loading does not bring the total resistance to turning so high as to 90 be at all prohibitive; but when the table is on a grade sloping some 4 or 5% and the truck approaches up hill, the best emplacement on the table that is possible will leave the center of gravity short of the center of 95 turning, so that in turning the center of gravity must be moved up hill. A five ton truck full loaded weighs about 24,000 pounds, and the theoretical work of turning 100

it is quite beyond the power of one man if conditions are such that its center of gravity must be moved up hill as much as 6 inches.

As a practical matter of fact, indeed, it is found virtually impossible for even three or four men to reverse a 5 ton truck on a turntable where there is a substantial grade.

The preferred embodiment of my invention hereinafter described overcomes these 10 defects and limitations of turntables hitherto used,—making it possible to balance and turn (full loaded) any commercial type of truck (if within the capacity of the table to receive it at all) on practically any grade 15 without disturbing the side rails of even a 16 foot roadway, while at the same time leaving room for trucks to pass the turntable in the roadway without driving over the table. This embodiment also obviates 20 all necessity for cumbersome and costly stationary ramps such as hitherto employed at the ends of road turntables.

How these and other advantages can be realized through my invention will appear 25 from my description hereinafter of the best embodiment of the invention at present known to me.

In the drawings, Fig. 1 is a somewhat 30 diagrammatic plan view of a turntable constructed in accordance with my invention, in place in one side of a roadway, and turned to extend lengthwise of the latter;

Fig. 2 is an elevation at right angles to Fig. 1, showing the turntable swung across 35 the roadway as in turning a truck;

Fig. 3 is a plan view of the turntable on a larger scale than Figs. 1 and 2, partly diagrammatic;

Fig. 4 is a corresponding side elevation; 40 Fig. 5 shows a longitudinal section through one of the trackways provided for the vehicle wheels in the form of turntable illustrated,—taken as indicated by the line 5—5 in Fig. 3;

Fig. 6 is a plan view of the rotating and stationary parts of the turntable, minus the trackways for the vehicle wheels;

Fig. 7 shows a corresponding longitudinal midsection, taken as indicated by the 50 line 7—7 in Fig. 6;

Fig. 8 is a corresponding end elevation, from the right of Fig. 6;

Figs. 9 and 10 show transverse sections through the movable turntable proper, 55 taken about as indicated by the lines 9—9 and 10—10 in Fig. 3, but on a larger scale; and

Figs. 11, 12 and 13 are side views of a shiftable ramp and supporting shoe mounted, with its operating mechanism, on one 60 end of the rotatable table,—showing the parts in several different positions.

The turntable illustrated in the drawing (see especially Figs. 1 and 2) comprises a 65 table structure 15 mounted to turn on a sta-

tionary supporting base 16 that rests on the subgrade *g*. Instead of being set very low, however, to turn between the side rails *r*, the table platform (or at least a considerable part of it) is elevated to such a height 70 (say about a foot above the subgrade) as to clear and swing over the rail *r* at one side of the roadway, and the berm, etc., beyond,—or any other ordinary obstructions. The absolute control of the road width over 75 the greatest radius of the table platform being thus transcended, the table is no longer limited as to overall length. It is perfectly feasible, then, to make the table 20 feet long or more, so as to permit even 80 the very longest motor trucks to be properly balanced on it. And with a truck substantially balanced on the table 15, neither the base structure 16 itself nor the outermost portion of the table structure that bears on 85 the base need be of very great width in order to keep the table from tipping under the truck even when turned crosswise of the roadway,—so that there is no essential difficulty whatever in so locating the turntable in one side of a 16 foot roadway (even) as to leave plenty of room for a 90 truck *T* to pass it in the other side when the table is turned lengthwise of the roadway. As shown, indeed, the base 16 is so 95 relatively narrow as never to be an interfering factor in reference to passage of vehicles in the other side of the roadway,—narrower than the table 15 itself, in fact. It is quite feasible, also, to place a truck 100 on the table with its center of gravity beyond the center of turning, so that the center of gravity shall move down hill and the weight of the truck thus assist the turning.

In the present instance, only the one overhanging end 17 of the turntable platform is elevated so as to clear the rail *r*, as described above. The other overhanging end 18 slopes gently downward to a point quite close to the ground, so as to serve as a ramp for a 105 truck going on or off the table. If, then, the elevated end 17 is made long enough to allow the longest truck to be balanced on the platform when facing toward that end, as shown (say some 12 feet from turning center to outboard extremity), the downward sloping ramp end can be made materially shorter, as shown (say some 8 feet from turning center to outboard extremity), so as to swing in the vacant side 110 of a 16 foot road, even, without difficulty.

In order to balance a truck on such a table, it may, indeed, be necessary to drive the truck (or at least any very long truck) on the table from the ramp end; but this 125 is much more than offset by the concomitant advantage of dispensing with a long, heavy stationary ramp for either end of the table.

Referring, now, also to Figs. 3, 4 and 5, it will be observed that in the present in- 130

stance the sloping ramp end 18 of the table is well clear of the ground (say some 3 or 4 inches) at its extremity, so that the usual inequalities of the subgrade *g* will not interfere with its movement at all. The ramp 18 is supplemented, however, with a relatively short auxiliary ramp or inclined shoe 20 (some 2 feet long or less), movably mounted at the extremity of the table end 18 so that it can be shifted into or out of ground engaging position, as occasion may require. When in ground-engaging position, this device 20 supports the table end 18 against tipping under the unbalanced weight of a truck in the act of mounting or leaving the table. When the ground is soft rather than perfectly hard and firm, a stout metal plate 21 (Fig. 4) may be placed in position to afford a firm bearing for the ramp shoe 20, and to prevent the ground from being cut away by the shoe heel in operation. As shown, auxiliary supporting means to prevent over-tipping are also provided for the elevated or long table end 17, in the form of a shoe 22 movably mounted at the extremity of this end 17 so that it can be shifted from ground-engaging position into an elevated position where it will clear the road rail *r* without difficulty. The support afforded the table end 17 by this device 22 prevents this end from tipping down on the ground in case a mounting truck is driven materially beyond balancing position on the table, or in case the wheel base length of the truck is so great that the front wheels pass beyond the turning tracks 27, 29 before the rear wheels have begun to mount the table at all, while the adjustability of this device 22 permits the table to swing freely with a properly balanced truck.

In order to avoid complications from inequalities of the ground, the anti-tipping supporting means 20, 22 at opposite ends of the table structure 15 may preferably be made separately operable, rather than provided with common or interconnected operating means.

As here shown (see also Figs. 6, 7 and 8), the base 16 comprises a bottom plate or "sled" 26 that rests on the ground, a circular supporting track 27 rigidly secured to the sled 26, so as to help in bracing and stiffening the latter, and a central hollow boss or stud 28 also rigidly secured to the sled 26, for the purpose of properly centering the rotary parts with reference to the base. The rotary table structure 15 has a circular track 29 (conveniently distinguished as the turning track) for cooperating with the base track 27, and is kept properly centered on the base by means of a pivot or king-pin 31 socketed in the hollow boss 28, and engaged in a hub part 32 of the table structure. As shown, the forward margin of the sled plate 26 is curved

upward somewhat, and provided with grab-eyes 33 for the attachment of a bridle chain for pulling the whole turntable forward along the subgrade (away from the mixer) from time to time, as the work advances. 70

In order to minimize the frictional resistance to turning of the rotary table structure 15, a multiplicity of anti-friction rollers 35 may be interposed between the base and table tracks 27 and 29, arranged in a circular series. As shown, these rollers 35 are mounted on axle spokes or rods 36 radiating from a common hub 37 mounted and centered on a bearing portion of the base stud 28, concentric with the tracks 27 and 29. Collars 38 fixed to the spoke-axes or rods 36 prevent inward displacement of the rollers 35; and a circumjacent hoop or circular band 40 mounted on the outer ends of the rods prevents outward radial displacement of the rollers and braces the rods. As shown, the ends of the rods 36 are merely engaged in downward-opening notches 41 in the band 40, so that the rods have some up and down play, and the rollers 35 are free for independent vertical self-adjustment to follow any irregularities of the rail freely (i. e., are never restrained by the band from bearing fully on the rail, even if the latter be "surface bent" from a flat circle), though held definitely spaced circumferentially. 85

Nuts 42 on the outer ends of the rods 36 hold the band 40 in place and in true circular shape. The rollers 35 may preferably be peripherally rounded or cambered somewhat (but not spherical), as shown, so that they shall not tend to bind on track or rods, and of very hard material, or case-hardened. 90

The table platform of the machine here shown is divided into two separate trackways 44, of convenient width (e. g., a couple of feet) for the vehicle wheels. Each of these trackways 44 has sides formed by a pair of longitudinal strength members 45 of channel cross section (arranged facing one another), and a floor of short, heavy planks 46 (Fig. 5) with their ends resting on the lower channel flanges. As shown, the side members 45 of each trackway 44 are interconnected and held in proper relative positions by channel-like cross bars 47 having at their ends feet riveted or otherwise secured to the lower channel flanges (in line with the turning center at 31), as well as by a transverse channel bar 49 extending and secured across the ends of all the side members 45 at the outboard extremity of the elevated table end 17, and serving as a stop or bumper to prevent a truck from accidentally running off the table at that end. 115

Besides the turning track 29, the structure for supporting the trackways 44 comprises a rectangular frame 50 overlying and secured to said track 29, and also transverse 130

members 51 (including pairs of channels arranged back to back) outside said track 29, connected to and supported by said frame 50. As shown, the frame 50 includes a pair of inward-facing longitudinal channel members 52 closely paralleling the inner trackway sides 45, and (like them) resting directly on the "base" of the inserted rail 29, and also a pair of transverse inward-facing channel members 53 with their ends resting on the rail 29, abutting and secured to the channels 51. Sheet metal strips 54 and 55 extend centrally lengthwise and crosswise of the frame 50, so as to intersect at its center, where the centering hub 32 is located. At their ends, the strips 54 and 55 are secured to the lower flanges of the channels 52 and 53, and at their intersection, they are secured together and to the hub 32 beneath them. The longitudinal frame members 52 overhang beyond the track 29, and in the construction illustrated, the supporting members 51 underlie the overhanging ends of these frame members, with their upper flanges directly against them. As shown, the transverse members 51 are secured to the frame members 52 by means of U-shaped yokes 56 that rest on the edges of correspondingly curved plates 57 riveted fast to the backs of the members 52. These yokes 56 straddle the pairs of channels forming the members 52, and their cross bars 58 (on which the latter rest) are secured to the yokes by nuts 59.

In the construction illustrated, the inner trackway sides 45 overlie and rest on the transverse members 51 and the track 29 beside the frame 50, and are secured to the frame members 52 by means of bolts 61 (see Fig. 9) extending through said members and the plates 57. The outer trackway sides 45 are secured to the outer ends of the supporting members 51 by means of bolts 62.

In order to permit the turntable to be used in a narrow roadway, it may be found desirable to provide clearance under the outer trackway edges sufficient to permit either trackway to overlap a roadrail *r* somewhat for most of or even the entire length of the trackway. As here shown, this is accomplished by making the outer portion of each transverse supporting member 51 in a separate piece 63 (riveted between the outer ends of the channels forming the member), with much of its depth above the lower edge flanges of the trackway sides 45, and with an upturned foot 64 abutting against the web of the outer trackway member just above the lower flange of the latter.

Referring, now, to Figs. 1 to 5 and 11 to 13, it will be observed that each trackway 44 is provided with a separate ramp shoe 20, and that each such ramp shoe is mounted to swing vertically about a transverse horizontal pivot or pivots 65, mounted in box-

like bracket structures 66 embracing and secured to the ramp ends of the trackway sides 45. A transverse shaft 67 for operating each device 20 is also mounted in the corresponding brackets 66, beneath the floor 46. Each end of the shoe 20 (speaking with reference to its extension transversely of the trackway 44) is provided with a crank extension 68 back beyond the pivot 65, and the operating shaft 67 has corresponding cranks 69 connected to said cranks 68 by pivoted links 71. As shown, these parts 68, 69, 71 are housed within the brackets 66, at the inner sides of the channel members 45. The interconnected members 69 and 71 have cooperating abutment or stop shoulders 72, for limiting the motion of the parts one way to a position in which the link pivots are in one straight line with the shaft 67,—or a little beyond. The adjacent ends of the two shafts 67 may be provided with readily removable operating levers 73, in convenient proximity for concurrent manipulation by a man standing between them.

When a truck is to drive on or off the turntable, the shoes 20 lie flat on the ground as shown in Figs. 3 to 5 and 11, and the "toggles" formed by the members 69, 71 are in their straightened position, and perfectly stable against any movement of the shoes 20 relative to the table structure 15. Hence the shoes 20 afford the ramp end 18 of the table firm and unyielding support against tipping under the weight of a truck, besides being themselves unaffected in any way by the truck as the latter drives over them to mount the ramp end 18.

When the truck is properly placed on the table and the latter is to be swung, the operator raises the levers 73 to the point shown in Fig. 12, thus lifting the ramp shoes 20 till the links 71 are straight with the cranks 68. Thereupon the operator pulls or pushes the shoes 20 up a little higher, past dead center, till downward movement of the levers 73 will act to swing them on up into the erect position shown in Fig. 13. In this position, the parts are substantially balanced and will not fall. If the shoes 20 are so massive that in order to counterbalance them in the position of Fig. 12 the levers 73 would have to be inconveniently heavy and cumbersome, swinging gravity-actuated pivoted catches 74 such as shown in Fig. 12 may be provided, to snap under the shoes 20 when they reach the position of Fig. 12 and keep them from falling.

Thereupon, the operator can swing the turntable as desired (by the levers 73).—after which he pushes the shoes 20 down again into the position shown in Fig. 11. In case the earth is a little high where a shoe 20 strikes it, the operator can finally push down on the levers 73, and thus exert great pressure to force the shoes down to final position.

- This description of the operation presupposes, of course, that the supporting shoe 22 of the elevated table end 17 is correspondingly manipulated,—if used at all. As shown in Figs. 3 and 4, the device 22 comprises a ground plate attached (at its ends) to the free ends of a couple of lever arms 75 fulcrumed at 76 on the adjacent sides of the inner trackway side members 45. A transverse operating shaft 77 extends clear across from side to side of the table structure adjacent the end member 49, and is provided with crank arms 78, which are connected by pivoted links 79 (of slightly bent form) with the shoe arms 75. As shown, the interconnected members 78 and 79 have cooperating abutment or stop shoulders 81, corresponding in function to the shoulders 72 of the parts 69 and 71. Either or both ends of the operating shaft 77 (outside the outermost trackway side members 45) may be provided with readily removable operating levers 83,—similar to the levers 73, and here shown as square socketed to fit the squared ends of the shaft 77. If desired, of course, the table 15 can be swung by one or both of the levers 83 as push bars, after the shoe 22 has been released from firm engagement with the ground.
- When the parts are in the positions shown in Fig. 4, the "toggle" formed by the members 78 and 79 is extended past dead center, and hence stable and uncollapsible under any load on the table,—so that the device 20 affords the table firm, unyielding support against tipping. When the lever 83 is swung over about 180°,—till the cranks 78 point upward, and the bends of the links 79 strike and rest against the shaft 77,—the shoe 22 is lifted between the trackways 44, where it does not affect the clearance room under the table end 18 at all.
- It will be observed that the turntable here illustrated is not only convenient and effective in use, but also easy and convenient to assemble or take apart quickly, and to transport from one job to another. For by simply taking out a few bolts, first the trackways 44 may be removed and separated from one another; then the transverse supporting members 51 removed; then the supporting frame 50 with its turning track 29 lifted off; and, finally, the anti-friction roller assembly removed from the base 16.
- What I claim is:
1. A roadway turntable comprising a rotatable table structure swingable over the road edge and itself serving as ramp for vehicles mounting or leaving it.
  2. A roadway turntable comprising a rotatable table structure swingable over the road edge, and itself serving as ramp for vehicles mounting it; and means carried by said table structure for engaging the ground to prevent overtipping of said structure by a mounting vehicle driven thereupon beyond balancing position.
  3. A turntable comprising a rotatable table structure swingable over a road edge and having its ends of unequal length to accommodate a full loaded truck of capacity size balanced on the table.
  4. A roadway turntable comprising a rotatable table structure with ends of unequal length to accommodate a full loaded truck of capacity size balanced on the table, the short end serving as ramp for vehicles mounting the table, and the long end swinging over the road edge.
  5. A roadway turntable comprising a rotatable table structure with ends of unequal length to accommodate a full loaded truck of capacity size balanced on the table, the short end serving as ramp for vehicles mounting the table, and the long end swinging over the road edge; and means carried by said long end for engaging the ground and preventing said long end from tipping down on the ground under the weight of a mounting vehicle driven upon the table structure beyond balancing position, said means being adjustable to permit the table to swing freely.
  6. A roadway turntable comprising a rotatable table structure swingable over the road edge, and itself serving as ramp for vehicles mounting it, and means comprising a ground shoe at one end of the table structure for preventing tipping down of such end on the ground by a vehicle driven on the table from the other end beyond balancing position; and means for elevating such shoe from ground engaging position comprising a lever adapted to serve as a push bar for swinging the table.
  7. A turntable comprising a rotatable table structure with one end elevated to swing over a road edge and of length to accommodate a full loaded truck of capacity size balanced on the table facing such end, and the other end sloping downward as a ramp and of length to swing within the other road edge.
  8. A turntable comprising a rotatable table structure with one end elevated to swing over a road edge and of length to accommodate a full loaded truck of capacity size balanced on the table facing such end, and the other end sloping downward as a ramp and of length to swing within the other road edge; and means carried by the table ends for engaging the ground to prevent tipping of the table by a vehicle, such means being shiftable to permit the table to swing freely.
  9. A turntable comprising a base adapted to be placed in one side of a roadway, and of such relatively narrow width as not to interfere with passage of vehicles in the other side of the roadway; and a rotatable table structure supported by said base to swing

over the road edge, itself serving as ramp for vehicles mounting or leaving it and of length to accommodate a full loaded truck balanced thereon so as not to tip the table structure even when the latter is turned crosswise of the roadway.

10. A turntable comprising a base adapted to be placed in one side of a roadway; and a rotatable table structure on said base leaving room for passage of vehicles in the other side of the roadway when turned to extend lengthwise of the latter, and having one end elevated to swing over a road edge and of length greater than the other to accommodate a full loaded truck of capacity size balanced on the table facing such end.

11. A turntable comprising a base adapted to be placed in one side of a roadway; and a rotatable table structure on said base leaving room for passage of vehicles in the other side of the roadway when turned to extend lengthwise of the latter, one end of said structure being elevated to swing over a road edge and of length to accommodate a full loaded truck of capacity size balanced on the table facing such end, and the other end sloping downward as a ramp and being of length to swing within the other road edge.

12. A turntable for road vehicles comprising a turning track; supporting structure overlying said track and overhanging therefrom, including transverse supporting members outside the track; a stationary base with supporting means for said turning track; overhanging trackways for the vehicle wheels overlying and supported by said transverse members beside the portion of said supporting structure overlying the track, sloping downward as ramps at one end, and at the other elevated to swing over a road edge and of length to accommodate a full loaded truck of capacity size balanced thereon facing such end.

13. A turntable for road vehicles comprising a stationary base with supporting track; a rotatable table structure with turning track; and a circular series of peripherally rounded anti-friction rollers interposed between said tracks, held definitely spaced apart circumferentially, but free for independent vertical self-adjustment relatively to one another.

14. A turntable for road vehicles comprising a stationary base with supporting track; a rotatable table structure with turning track; and an anti-friction roller assembly comprising spoke-axes, a circular series of rollers interposed between said tracks, and a notched band engaging said axes and spacing them apart circumferentially while permitting them independent freedom of vertical self-adjustment, and also preventing radial displacement of the rollers.

15. A turntable for road vehicles com-

prising a rotatable table structure; and ramp means carried by the table end shiftable relatively thereto into and out of ground engaging position, and when in such position supporting the table end against tipping.

16. A turntable for road vehicles comprising a rotatable table structure; vertically swinging ramp means pivoted to the table end; and means for swinging the ramp means into and out of ground engaging position, including toggle means stable against movement of the ramp means when the latter is in ground engaging position.

17. A roadway turntable comprising a sled base, a supporting structure rotatable on said base; and trackways for the vehicle wheels resting on said supporting structure, swingable, by its rotation, over a road edge, and themselves serving as ramps for vehicles mounting or leaving the turntable.

18. A roadway turntable comprising a base, a supporting frame rotatable on said base, and trackways for the vehicle wheels beside said frame, with supporting means for said trackways carried by said frame and extending from either side thereof beneath the trackways.

19. A revolving turntable for road vehicles comprising trackways for the vehicle wheels, transverse supporting members extending beneath said trackways, a turning track between said members, and structure overlying said track connected thereto and to said members for transmitting the load of the trackways from the latter to the former.

20. A revolving turntable for road vehicles comprising a revolving turning track, a supporting frame structure mounted on and overlying said track, and separate trackways for the vehicle wheels detachably secured beside said frame structure at either side thereof.

21. A roadway turntable comprising a revolving turning track, a frame structure mounted on and overlying said turning track, and trackways for the vehicle wheels resting on said turning track beside said frame structure.

22. A revolving turntable for road vehicles comprising trackways for the vehicle wheels, a turning track, a supporting frame overlying said track, and transverse supporting members for said trackways subjacent the same and said frame supported by the latter.

23. A revolving turntable for road vehicles comprising a turning track; a supporting frame structure mounted on and overlying said track, with transverse supporting members extending to either side therefrom; and separate trackways for the vehicle wheels at either side of said frame structure, with inner lateral strength members resting

on said transverse supporting members, and outer side members secured to the ends of said transverse members.

24. A revolving turntable for road vehicles comprising trackways for the vehicle wheels, with inner and outer lateral strength members; transverse supporting members for the trackways secured to said strength

members; a turning track between said transverse members; and a frame mounted 10 on and overlying said track, with members overhanging and supporting said transverse members.

In testimony whereof, I have hereunto signed my name.

WILLIAM M. VENABLE.
